ABSTRACT OF THE DISCLOSURE

Transparent panel segments which are suitable for covering the walls of a building form a segmented receptacle panel for a design bearing web which extends upward through said receptacle between the segmented panel and the structure of the building and a plurality of said segmented vertical panels are interlocked and interconnected to form a wall covering. Said design bearing web is carried and supported between two roller mechanisms, one of each being located at the top and bottom of said segmented panel. Drive means connected to the top roller of the top roller mechanism serves as a means for changing the decorative designs of said segmented panel and the wall covering by winding up the design bearing web and shifting the exposed portion of said design bearing web to position a new portion of said web bearing a different design behind said segmented front member of said segmented panel.

This invention concerns an apparatus and process for a movable wall surface covering for the outside walls of buildings or the inside walls of the rooms of said buildings and more particularly a movable transparent printed film located in a transparent receptacle which is attached to said walls.

One of the objects of this invention is to provide a process for changing the printed designs on the outside surface of a building or a process for changing the printed designs on the surface of the walls of a room in a building.

Another object of this invention is to provide an apparatus for changing the printed designs on the outside surface of a building by means of a set of rollers and printed film.

The objects of this invention are accomplished by attaching two rollers at the top and bottom of a interlocking plurality of long one-unit, segmented, plastic, transparent, channel shaped, interconnected receptacle, wall panels which are composed of a series of short, separate, plastic, rectangular, receptacle, wall panel sections, which were previously mounted on the wall of the building. A transparent film with a printed design on its outer surface is wound around and connected to both top and bottom rollers so that by rolling up or winding up the top roller it is possible to wind up a given length of film which is located in the one-unit receptacle and has one printed design and to bring into place another length of film which has another different printed design on its outer surface so that the printed designs on the outside side walls of the building can easily be changed. At night, sets of lights are switched on so that the printed design is more easily noticed since the light passes through the transparent film. The transparent receptacles are interconnected with each other so that dust and dirt do not get on the printed transparent film and so that an integrated, interlocking, wall covering system structure is formed.

FIG. 1 is a top plan view of the apparatus for changing the printed designs on the outside walls of buildings or on the inside walls of rooms of said building.

FIG. 2 is a side plan view of the apparatus shown in FIG. 1.

FIG. 3 is a side plan view of the transparent front wall of the transparent receptacle which faces the outside.

2

Referring to FIG. 1 and FIG. 2 there is shown a top plan view and a side plan view respectively of the apparatus for changing the printed designs on the outside walls of buildings or rooms in which numeral 1 designates the channel shaped, plastic, transparent, rectangular, receptacle, wall panel section which consists of side walls 19 which can be either transparent or painted so as to be non-transparent and also the transparent front wall 1B through which can be seen the printed film and the partial back walls 15 and 15A which form inwardly extending flanges or extensions which interlock with adjacent outwardly extending flanges 22-22A of the other two transparent receptacles 20, 16 one on either side of said first transparent receptacle 1 and which locks said two other transparent receptacles 16, 20 in place as well as receiving a nut 5 and bolt 4 through a hole in said flanges 15 and 15A which firmly attaches said alternate first transparent receptacle wall panel segment and its two intermediate adjoining transparent receptacle wall panel segments, by means of said flanges to the outer walls 24 of the building or to the walls 24 of a room in said building. The two side wall members 19 of the wall panel segments 1 are connected at one end to the transparent front member 1B, which is spaced apart from the wall of the building to form a receptacle, wherein is located the printed film or web, along one pair of its opposite side edges and are connected at their other end to flanges so that the side wall members and their associated flanges of said first alternate panel segment 1 are joined to the side wall members and their associated flanges of the second and third intermediate panel segments 16, 20 so as to be interlocked and interconnected by the fastening means or bolts and nuts.

The top roller 3 of the two rollers is keyed on a shaft 25 which is attached and turns in ball bearing pillow blocks 26, 26A located in the side walls of transparent receptacle 1. By means of a hand crank (not shown) or by means of an electric gear winding motor (not shown) which is properly grounded to prevent electric shock to human beings and is connected to the single unit shaft 25 on which are mounted all of the top rollers, said top rollers can be turned and the printed films or webs wound up at the same time. The bottom roller of the bottom roller mechanism is similar to the top roller of the top roller mechanism in that it consists of a roller mounted in suitable supporting elements. The transparent film 2 with its printed design on its outer surface is wound around and connected to rolls of film on both top and bottom rollers 3, 3A (FIG. 2) so that by rolling up or winding up the top roller 3, it is possible to wind up a given length of film 2 having one printed design and to bring into place another length of film which has another different printed design on its outer surface so that the printed designs on the outside walls of the building can easily be changed. At night sets of lights 6 attached to socket board 7 which is mounted on an electrically insulating material which is attached to the wall of the building, are switched on so that the light passes through the printed film and the printed design is more easily noticed. The transparent receptacles are interconnected at their lengthwise ends as well as their sidewise ends so that dust and dirt can not get on the printed transparent film. It would be possible to automatically wash the walls of said transparent receptacles by allowing a fine pure, harmless, clean, city tap water spray 41 at the top floor of the building supplied by a pipe 40 with tiny holes which extends around the entire top floor perimeter of the building to hit upon the outside surface of the building and run down the sides of said building, thus the water would wash all of the receptacles on its way down the side of the building and no manual washing would be necessary.

FIG. 3 shows a side plan view of the transparent front wall of the transparent receptacle which faces outside and

numerical 1B designates the front wall of a first transparent receptacle wall panel segment 50, which is attached to the outer side walls 24 and has a transparent film 2 passing through it and said front wall 1B has tongues or projections 34A and 34 which fit into grooves 35A and 35 of receptacles 52 and receptacle 57 respectively at points 33 and 33A so that the receptacles 50, 57, 52 are interlocked in a lengthwise direction at their front transparent walls, at their top and bottom edges so that no dirt and dust can get onto the plastic film. The plastic film 2 may consist of a flexible transparent or translucent non-breakable type of plastic film such as unoriented or oriented safe polypropylene or safe acrylic or other safe plastic materials suitable for building purposes and the transparent receptacles may consist of safe polypropylene or safe non-breakable acrylic or other safe plastic materials suitable for building purposes, preferably extruded to form said panel segments. It is necessary to use safe plastic materials suitable for building purposes in order to prevent hurting human beings.

It is necessary for the purpose of safety and to prevent the receptacles from ever coming loose and falling to the ground from the outside surface of the building and thus prevent hurting some human being that the receptacles are riveted together by rivets 50 at their flanges 15 and 15A so they are joined in a widthwise direction and also rivets 50 may join two receptacles in a lengthwise direction. If the top receptacle flange is positioned properly in relation to the bottom receptacle flange so that even greater safety is made possible. Preferably, the transparent receptacles are bolted or riveted together according to the known prior art. Thus the transparent receptacles are firmly joined together by rivets in a lengthwise as well as a widthwise direction so all of the receptacles are interconnected for greater strength and safety to form an integrated wall covering system structure.

Therefore, this invention includes all modifications within the spirit and scope of the following claims:

I claim:

1. A wall covering for buildings comprising,
  - (I) A plurality of vertical wall panels, each panel comprising
    - (A) a front member and a pair of side members,
    - (B) said front member being transparent and spaced from said wall to form a receptacle,
    - (C) said side members connecting said front member to said wall
    - (D) said side members being joined with side members of adjacent panels,
  - (II) each of said panels further comprising
    - (A) a plurality of rectangular segments having top, bottom, and side edges,
    - (B) each of said segments having means along its top and bottom edges for joining the segments with adjacent segments of said panel,
    - (C) each of said segments having means along its side edges for joining the segments with adjacent segments of adjacent panels,
  - (III) a display bearing web between said wall and said front member and extending between the top and bottom of said panel,
  - (IV) means for changing the display of said panel and its display bearing web and thereby changing the display of said wall covering and said walls of said building whenever desired,
  - (V) means for illuminating the panel and its display bearing web and thereby illuminating said wall covering and said walls of said building.

2. The wall covering for buildings provided in claim 1 in which the means for changing the display of said wall panel and its display bearing web and thereby changing the display of said wall covering comprises a first top roller mechanism having a roller mounted on a shaft in supporting elements and drive means connected to said shaft for rotating the roller and its associated roll

of web to wind up and move a first predetermined length of web bearing a first decorative design area out of the vertical panel and bring a second predetermined length of web bearing a second different decorative design area into place behind the transparent front wall of said panel, the decorative design bearing translucent web which is attached to a roll of web mounted on the roller of a second bottom roller mechanism and is conveyed and extends upwardly in said vertical panel of said wall covering between the transparent front wall of said segmented panel and the structure of said building and is connected to a roll of web mounted on the roller of said first top roller mechanism, said second bottom roller mechanism having a roller on a shaft mounted in supporting elements.

3. The wall covering for buildings provided in claim 1 in which the means for illuminating the decorative design of said panel and its design bearing web comprises a series of electric sockets bearing electric light bulbs mounted on an electrical insulating material which is mounted on the structure of the building.

4. The wall covering for buildings as provided in claim 1 in which said means for joining the panel segments along their side edges with adjacent panels and for attaching said segments to said wall comprises a plurality of outwardly extending flange elements angularly connected to said vertical parallel side wall members of the segments of alternate panels in said plurality of wall panels comprising said wall covering, a plurality of inwardly extending flange elements, angularly connected to said vertical parallel side wall members of said segments of the remaining intermediate panels of said plurality of wall panels comprising said wall covering, said outwardly extending flange elements of said segments of said alternate panels extending behind said inwardly extending flange elements of said segments of the remaining intermediate panels, whereby said flanges of adjacent wall panel segments overlap each other to interlock said wall panel segments along their vertical side wall edges, said wall panel segments are interconnected at said flange elements by fastening means which join said wall panel segments together, said fastening means also attach said wall panel segments to said wall and means for joining the alternate segments of said panel along their top and bottom edges with adjacent segments of said panel comprises tongue or projecting portions and means for joining the remaining intermediate segments of said panel along their top and bottom edges comprises groove or recessed portions, said tongue and groove portions of said alternate and intermediate segments of said panel engage with each other to interlock said segments along their top and bottom edges.

5. The wall covering for buildings as provided in claim 1 in which the wall panel segments comprise safe plastic, polymeric, resinous, material suitable for building purposes which are heated and shaped to form said wall panel segments.

6. The wall covering provided in claim 5 in which the wall panel segments comprise safe plastic, polymeric, resinous materials suitable for building purposes which are extruded to form said wall panel segments.

7. The wall covering provided in claim 1 in which the means for changing the display of said panel and display bearing web comprises a means for changing the printed or drawn decorative designs and decorative illustrations of said panel and its web further comprising a means for shifting the exposed portion of said design or illustration bearing web to position a new portion of the web bearing a different design or illustration behind said front member of said segmented panel.

8. The wall covering provided in claim 1 in which said wall panel segments are positioned so that first and second panel segments located on the top and bottom edges of a third panel segment are interlocked with said third panel segment, one top tongue or projecting portion of

said third panel segment engaging with the groove or recessed portion of the bottom edge of said first panel segment and the other bottom tongue or projecting portion of said third panel segment engaging with the groove or recessed portion of the top edge of said second panel segment.

9. The wall covering provided in claim 1 in which said panel segments are secured to the outside walls of the building and the inside walls of said building or rooms and said panel segments are mounted on the inside and outside portions of the structural framework of the outside walls of said building to form a building component system comprising a wall covering system structure.

10. The wall covering provided in claim 1 in which said wall panel comprises a series of segments joined at their top and bottom edges to form a segmented transparent wall panel having a channel shaped receptacle area, a first top roller mechanism being attached at the top of said segmented wall panel and a second roller mechanism being attached at the bottom of said segmented wall panel, a decorative design bearing web being attached to the roll of the second bottom roller mechanism and extending upwardly in said channel shaped receptacle area and being connected to the roll on the first top roller mechanism, a drive means being connected to a shaft on which the roll of the first top roller mechanism is mounted for shifting said web and changing the design of said panel and its exposed design bearing web located behind the front segmented member of said segmented panel.

11. The wall covering provided in claim 1 wherein said wall covering comprises a plurality of segmented wall panels attached to a supporting building structure, said segmented wall panels being positioned such that at least first and second segmented panels located on one pair of opposite side edges of a third segmented panel, are attached in overlapping relationship with said third segmented panel, one flange of said third segmented panel engaging with a flange extending from the side wall member of said second segmented panel and the other flange of said third segmented panel engaging with the flange extending from the side wall member of said first segmented panel.

12. The wall covering as provided in claim 1 wherein each side member of said panel segment is angularly connected to a projecting flange element and said side members are angularly connected to said front member on one pair of its opposite edges.

13. The wall covering as provided in claim 2 wherein said side members are angularly connected to projecting flange elements and fastening means hold said projecting flange elements to said wall and join the overlapping and interlocking flange elements of said panel segment and of adjacent panel segments together.

14. The wall covering as provided in claim 1 in which

said panel segments are channel shaped and said panel segments are inter-connected and overlapping with adjacent panel segments along their side walls flanges by fastening means and said segmented panels serve as building components.

15. The process for changing the display of a wall covering for buildings which comprises the steps of mounting and assembling a series of wall panel segments on the wall structure of a building so that they are joined along their vertical side wall edges and along the horizontal top and bottom edges of their front transparent walls in order to form a weatherproof wall covering comprising a plurality of vertical joined segmented wall panels and thereafter mounting first roller mechanisms at the top of the vertical segmented wall panels and mounting second roller mechanisms at the bottom of said panels and conveying the webs bearing the decorative designs from the rolls of webs mounted on said second bottom roller mechanisms in an upwardly direction through the hollow portions of said segmented panels and winding the ends of said design bearing webs around the rollers of said first top roller mechanisms comprising rollers on shafts mounted in supporting elements and rotating the rollers and their associated rolls of webs of said first top roller mechanisms by drive means connected to said shafts to wind up and move a first predetermined length of webs bearing a first decorative design area out of the vertical segmented panels and thus bring a second predetermined length of webs bearing a second different decorative design area into place behind the transparent front walls of said segmented panels from the rolls of webs mounted on said second bottom roller mechanisms and thus changing the display of said segmented wall panels and their display bearing webs and thereby changing the display of the wall covering and the walls of said building.

16. The process for changing the display of said wall covering as provided in claim 15 wherein said process for changing said display of said wall covering comprises the steps of changing the printed or drawn design or illustrations of said panels and their webs and thereby changing the designs and illustrations of said wall covering and the walls of said building.
